UNITED STATES PATENT OFFICE.

WILLIAM H. AMES, OF ST. LOUIS, MISSOURI.

VICE.

SPECIFICATION forming part of Letters Patent No. 613,351, dated November 1, 1898.

Application filed May 16, 1898. Serial No. 680,797. (No model.)

To all whom it may concern:

Be it known that I, WILLIAM H. AMES, a citizen of the United States, and a resident of the city of St. Louis, in the State of Missouri, have invented certain new and useful Improvements in Vises, of which the following is a full, clear, and exact description, reference being had to the accompanying drawings, forming part of this specification.

10 My invention relates to a vise which is provided with detachable jaws; and my invention consists in features of novelty hereinafter fully described and claimed.

15 Figure I is a side elevation illustrating my invention. Fig. II is an edge view of the same. Fig. III is a side view thereof in horizontal position. Fig. IV is a cross-sectional view taken on the line IV IV, Fig. I. Fig. V is a detail top view showing the vise-jaws in 20 closed position. Fig. VI is a side view showing the vise-jaws in open position. Fig. VII is a similar view to Fig. VI, showing the vise-jaws closed and the bifurcated shanks at one side of the jaws broken away.

25 1 designates the fixed stem of the implement, which at one end is provided with a neck 2 and a ball 3. The ball 3 is seated in the socket 4, contained by a base 5, the ball being held in the socket by a cap 6, securely 30 fastened. This arrangement provides a universal ball-and-socket joint between the stem 1 and the base 5 for the purpose of permitting the stem to be maintained in an upright position regardless of whether the foundation 35 on which the base is seated is level or otherwise. The opposite end of the stem 1 is provided with openings 1^a, extending therethrough, the purpose of which will hereinafter appear.

40 7 designates a double ratchet-bar joined at one end by a sleeve 8, that surrounds the stem 1, and is adapted to slide with the ratchet-bar thereon. The opposite or outer end of the ratchet-bar is joined by a head 9, having 45 prongs 10 and cut-away portions providing side recesses 11.

45 12 designates a hand-lever pivoted at 13 to the fixed stem 1. The lever is forked to straddle the ratchet-bar 7, and the stem, with its 50 inner end, extends beyond the pivot.

14 are gripping-loops pivoted to the lever

12 at each side of the pivot of the lever. These loops are designed to engage the teeth of the ratchet-bar 7, and they are provided with arms 15, that may be grasped by the operator's fingers to throw the loops out of engagement with the ratchet-teeth when they are relieved from strain and it is desired to lower the ratchet-bar on the stem.

16 designates a prong on the stem 1, that is 60 designed to be placed against a post A or other suitable object to receive the strain of wire in the stretching operation. The point of the prong 16 is intended to bite into the post A to prevent the stretcher from slipping 65 from the post. On the sleeve is a boss 17 and a cam-lever 18.

19 is a stop on the sleeve 8, adapted to limit the movement of the cam-lever. In stretching wire the wire indicated by B is inserted 70 between the boss 17 and the cam-lever 18, and the cam-lever is turned to clamp the wire between these parts.

75 A pair of jaws 20 is applied to the stem. The shanks 21 of the jaws are bifurcated to straddle the central portion 11 of the head 9 at the ends of the ratchet-bar. The jaws 20 are detachably connected to the stem 1 by pins 22, passing through the jaw-shanks, the pins being inserted in the openings 1^a, contained by the stem. In the upward movement of the ratchet-bar 7 the jaws 20 are 80 forced toward each other in the head 9, moving from the position shown in Fig. VI to that shown in Fig. VII. By detachably connecting the vise-jaws to the stem 1 they may be 85 readily removed, when the device may be used as a hoisting-jack or wire-stretcher.

Having thus described my invention, the following is what I claim as new therein and 90 desire to secure by Letters Patent:

The combination of a stem, a double ratchet-bar movable on said stem, means for moving said ratchet-bar, a head carried by said ratchet-bar and having cut-away portions, and a pair 95 of vise-jaws adapted to fit said cut-away portions and detachably connected to said stem; substantially as described.

WM. H. AMES.

In presence of—

E. S. KNIGHT,

N. V. ALEXANDER.
